UNITED STATES PATENT OFFICE.

HOWARD C. WARFIELD, OF BROOKLYN, NEW YORK.

WINDOW-SCREEN.

No. 892,918.

Specification of Letters Patent.

Patented July 7, 1908.

Application filed June 27, 1907. Serial No. 381,105.

To all whom it may concern:

Be it known that I, HOWARD C. WARFIELD, a citizen of the United States, residing at Brooklyn, in the county of Kings and State 5 of New York, have invented certain new and useful Improvements in Window-Screens; and I do declare the following to be a full, clear, and exact description of the invention, such as will enable others skilled in the art to 10 which it appertains to make and use the same.

This invention relates to improvements in window screens.

The object of the invention is to provide a 15 screen of this character constructed and arranged so as to permit the looking out of the window in any direction without removing the screen, and by means of which the flies and insects which may be on the inside of the 20 screen can be readily turned out.

With this object in view, the invention consists of certain novel features of construction, combination and arrangement of parts as will be more fully described and particu- 25 larly pointed out in the appended claims.

In the accompanying drawings, Figure 1 is a 30 perspective view of a window showing the application of the screen thereto; Fig. 2 is an inner side view of the window screen, parts 35 of the latter being broken away, and in section; Fig. 3 is a vertical sectional view; Fig. 4 is a horizontal sectional view; Fig. 5 is a detail vertical sectional view of a portion of one side of the screen frame, showing one of 40 the notched blocks engaged with the fastening pin of the window frame; and Fig. 6 is a detail perspective view of one of the fastening blocks.

Referring more particularly to the drawings, 1 denotes the screen frame which is adapted to fit within a window frame and the latter being preferably provided with strips, 2, arranged at each side of the screen frame, said strips being suitably fastened to the inner sides of the window frame, as shown. On the strips 2 are upper and lower inwardly 45 projecting screen supporting pins or bolts 3, the inner end of which is preferably provided with a head, 4.

50 Adapted to be set into the opposite sides of the bars of the screen frame are fastening or supporting blocks, 5, said blocks being provided with upwardly inclined slots or notches, 6. To the upper walls of the 55 notches 6 are fixed curved securing springs, 7, the inner ends of which are bent to form a

seat 8. When the screen frame is inserted in a window, the notches 6 are engaged with the pins or bolts 3, which, when the screen is in place, are disposed in the upper ends of the notches 6, and in engagement with the seats 8 of the springs 7, the curved portion of which prevents the casual displacement or removal of the screen frame. 60

To the outer sides of the screen frame 1, 65 adjacent to the upper and lower ends, are secured outwardly projecting curved or bowed screen supporting rods 9, around which is secured a wire netting screen 10, the inner edges of which are tacked or otherwise suitably secured to the side strips of the screen frame, as shown, said edges being preferably covered by a binding strip 12. The inner ends of the rods 9 are secured to the screen frame by brackets 9^a, on which are formed 70 sockets, through which the ends of the rods are passed. To the upper rod 9 is secured a semi-circular piece of netting 13, which forms the top of the screen. The inner edge of said netting is secured to the upper cross piece of 75 the screen frame, said edge being covered by a binding strip 14. Secured to the lower rod 9 is a semi-circular piece of netting 15, which forms the bottom of the screen, and is covered by a binding strip 16. Over the 80 meeting edges of the side, top and bottom pieces of the screen where the same joins or is connected to the supporting rods 9, are preferably secured binding strips, 17. 85

In applying the screen to a window, it is 90 simply necessary to engage the lower ends of the notches 6 of the fastening blocks 5 with the supporting bolts 3 and to force the screen downwardly until said bolts are engaged with the upper ends of the notches and rest in the 95 seats of the securing springs 7. In removing the screen from a window, it is simply necessary to push the same upwardly until the supporting pins or bolts 3 are opposite the lower open ends of the notches 6, after which the 100 screen may be readily pushed outwardly and disengaged from the supporting pins. 100

Having described my invention, what I claim as new, and desire to secure by Letters-Patent, is:

1. A window screen comprising a frame, a semi-cylindrical screen secured to the outer side of said frame, and projecting outwardly beyond the window, upper and lower fastening blocks inserted in the side pieces of the 110 screen frame and having formed therein upwardly inclined notches, strips arranged on

the inner sides of the window frame, and headed fastening pins secured to said strips and adapted to be engaged by said notched fastening blocks to detachably secure the 5 screen in place, substantially as described.

2. A window screen comprising a frame, upper and lower curved or bowed screen supporting rods secured at their inner ends to said screen frame, wire netting top, bottom 10 and sides secured to said rods and frame to form a semi - cylindrical screen, fastening blocks secured to the inner side of the screen frame, said blocks having formed therein upwardly inclined notches, supporting bolts or 15 pins arranged in the sides of the window frame and adapted to be engaged by said notched blocks to support the screen in place, and means to prevent the casual disengagement of the screen from said pins or bolts, 20 substantially as described.

3. A window screen comprising a frame, upper and lower curved or bowed screen supporting rods secured at their inner ends to said screen frame, wire netting top, bottom 25 and sides secured to said rods and frame to form a semi - cylindrical screen, fastening blocks secured to the inner side of the screen frame, said blocks having formed therein upwardly inclined notches, supporting blocks 30 or pins arranged in the sides of the window

frame and adapted to be engaged by said notched blocks, and springs arranged in said blocks to engage said bolts or pins thereby preventing the casual disengagement of the screen therefrom, substantially as described. 35

4. A window screen comprising a frame, upper and lower curved or bowed screen supporting rods secured at their inner ends to said screen frame, wire netting top, bottom and sides secured to said rods and frame to 40 form a semi - cylindrical screen, fastening blocks secured to the inner side of the screen frame, said blocks having formed therein upwardly inclined notches, strips arranged on the inner side of the window frame, headed 45 supporting pins or bolts arranged in said strips and adapted to be engaged by said notched blocks to hold the screen in place, and curved springs arranged in said notches to engage said pins or bolts and thereby prevent the casual disengagement of the screen frame, substantially as described.

In testimony whereof I have hereunto set my hand in presence of two subscribing witnesses.

HOWARD C. WARFIELD.
